US0D1053167S

(12) **United States Design Patent** (10) **Patent No.:** **US D1,053,167 S**
(45) **Date of Patent:** **** Dec. 3, 2024**

(54) **EARPHONES AND CHARGING CASE SET**

Primary Examiner — Paula Allen Greene

(71) **Applicant:** **TOZO INC**, Seattle, WA (US)

(57)

CLAIM

(72) **Inventor:** **Qi Lin**, Shenzhen (CN)

The ornamental design for earphones and charging case set as shown and described.

(73) **Assignee:** **TOZO INC**, Seattle, WA (US)

(**) **Term:** **15 Years**

(21) **Appl. No.:** **29/909,564**

DESCRIPTION

(22) **Filed:** **Aug. 8, 2023**

(30) **Foreign Application Priority Data**

Jun. 6, 2023 (CN) 202330343826.8

FIG. 1 is a perspective view of earphones and charging case set showing my new design;

(51) **LOC (14) Cl.** **14-01**

FIG. 2 is a perspective view of a charging case of the earphones and charging case set, shown separately for ease of illustration and in an open configuration;

(52) **U.S. Cl.**

FIG. 3 is another perspective view thereof;

USPC **D14/223; D13/108**

FIG. 4 is a front elevational view thereof;

(58) **Field of Classification Search**

FIG. 5 is a rear elevational view thereof;

USPC D14/223; D13/108; D3/274, 294, 201;

FIG. 6 is a left side elevational view thereof;

D28/83, 78, 91, 82; D9/420, 424, 529;

FIG. 7 is a right side elevational view thereof;

206/702, 565; 220/4.22, 4.02

FIG. 8 is a top plan view thereof;

CPC H04R 1/10; H04R 1/105; H04R 25/00;

FIG. 9 is a bottom plan view thereof;

H04R 25/02; H04R 1/106; H04R

FIG. 10 is a perspective view of earphones of earphones and

1/1016; H04R 1/1058; H04R 1/08; B65D

charging case set, shown separately for ease of illustration;

85/00; B65D 25/10; B65D 43/16; A45D

FIG. 11 is another perspective view thereof;

33/006

FIG. 12 is a front elevational view thereof;

See application file for complete search history.

FIG. 13 is a rear elevational view thereof;

(56) **References Cited**

FIG. 14 is a left side elevational view thereof;
